UNITED STATES PATENT OFFICE.

FRANK F. AMSDEN, OF MALONE, NEW YORK.

DESIGN FOR A SHOULDER-GARMENT.

SPECIFICATION forming part of Design No. 30,867, dated May 23, 1899.

Application filed April 23, 1898. Serial No. 878,678. Term of patent 31 years.

To all whom it may concern.

Be it known that I, FRANK FLOYD AMSDEN, a citizen of the United States, residing at Malone, in the county of Franklin and State of New York, have invented and produced a new and original Design for a Shoulder-Garment, of which the following is a specification, reference being had to the accompanying drawing, forming part thereof.

5 The leading feature of the design consists in the unitary article of apparel made the subject of the illustration, the same being shown in plan extended flat.

A minor feature of the design is the straight lower edges e and f of the back and front and 15 the curved lines of the sides g.

What I claim is—

The design for a shoulder-garment, as shown and described.

FRANK F. AMSDEN.
